UNITED STATES PATENT OFFICE.

CORNELIUS G. BRADSHAW, OF BUTTE, MONTANA.

DESIGN FOR A BADGE.

SPECIFICATION forming part of Design No. 25,037, dated January 7, 1896.

Application filed December 3, 1895. Serial No. 570,960. Term of patent 3½ years.

To all whom it may concern:

Be it known that I, CORNELIUS G. BRADSHAW, a citizen of the United States, residing at Butte, in the county of Silver Bow and 5 State of Montana, have invented and produced a new and original Design for Buttons or Badges; and I do declare the following to be a full, clear, and exact description of the same, reference being had to the accompanying 10 drawing, forming a part thereof.

The invention relates to a new and original design for buttons or badges; and it consists in the peculiar emblematical and decorative features upon the face of the badge—to wit: 15 the representation of a flag and a bug in the attitude of devouring the flag.

The design is shown in the accompanying drawing, in which the figure is an elevation of the face of a button or badge embodying 20 my design.

Arranged centrally upon the face A of the

button or badge is the representation of a United States flag B, the same being shown as attached to a staff a and unfurled and waved and with its free end extending downwardly, as indicated by b. Beneath the representation of the flag B, with its head contiguous to the end b thereof, is the representation of a bug C. This bug C is arranged, as illustrated, with its head contiguous to and partly covering the end b of the flag B in the attitude of devouring the flag. 25

What I claim is—

The design for a button or badge as herein shown and described. 35

In testimony whereof I affix my signature in presence of two witnesses.

CORNELIUS G. BRADSHAW.
